CLAIM

We claim the ornamental design for a bra, as shown and described.

DESCRIPTION

FIG. 1 is a right, rear perspective view of a bra, showing our new design;

FIG. 2 is a left, rear perspective view thereof;

FIG. 3 is a rear view thereof;

FIG. 4 is a left side view thereof; and,

FIG. 5 is a right side view thereof.

The dot-dash broken line represents an unclaimed boundary of the claimed design. The broken lines depicting the remainder of the bra show features that form no part of the claimed design.
